MERCURATED ALKYL AMIDES OF DIBASIC PHENYLENE ACIDS AND HOMOLOGUES THEREOF

Donalee L. Tabern, Lake Bluff, Ill., assignor to Abbott Laboratories, North Chicago, Ill., a corporation of Illinois

No Drawing. Original application May 15, 1939, Serial No. 273,725. Divided and this application June 1, 1942, Serial No. 445,318

6 Claims. (Cl. 260—434)

The present invention relates to pharmaceutical compositions and has for its principal object the preparation of novel compounds possessing properties making them adaptable for use in the diuretic field. A more specific object of the present invention is to provide mercurated alkyl amides of dibasic phenylene acids possessing diuretic activity of the type desired.

Certain types of mercury compounds in which the mercury group is attached to either an inorganic or organic radical, have the property of producing diuresis. Inorganic compounds of mercury, however, are highly toxic and the ratio between the effective dose and the toxic dose is such as to preclude their effective use in the diuretic field. The same difficulty exists in the case of most organic compounds of mercury, which are either too high in toxicity or too low in the desired therapeutic effectiveness for use in the medical art.

I have discovered that mercury derivatives of alkyl amides of dibasic aromatic acids, especially mercurated propyl amides of phthalic acid, are particularly effective diuretics, because of their high efficiency and relatively low toxicity. In other words, the compounds of the present invention possess a low diuretic dose and the ratio of the effective therapeutic dose to the toxic dose is unusually high. Of great importance, the new compounds are well tolerated during repeated injections. In addition, the compounds included in the present invention are soluble (or capable of being solubilized) and form stable solutions particularly adaptable for hypodermical administration.

The dibasic aromatic acids suitable for use in the present invention may be illustrated by the following general formula:

in which R_1 represents an aromatic ring such as the phenyl group;

in which R_2 represents

(a) Hydroxyl (OH) group.

(b) Salt O-metal group such as $-\text{O}-\text{Na}$;

and in which R_3 represents an active alkylene amide group such as

(c)

group in which Z represents a hydrogen atom, saturated and unsaturated alkyl groups.

(d)

group, or

(e)

group, where W represents a whole number.

The following specific examples of reactive alkylene amides of phthalic acid derivatives coming within the scope of the present invention will serve for illustrative purposes:

1. Monoallyl amide of phthalic acid.

2. Monoallyl amide of sodium phthalate.

45 3. Di-allyl amide of sodium phthalate.

4. Monoallyl ureide of sodium phthalate.

5. Monocrotonyl amide of sodium phthalate.

In the general formula above R_2 may also be an amide group including amide groups substituted with saturated and unsaturated alkyl groups and hydroxy alkyl groups. Examples of such reactive alkylene amides are:

6. Bis-monoallylamide of terephthalic acid.

7. Monobutenyl amide; methyl, amyl amide of phthalic acid.

Amide derivatives of this type form the subject matter of my co-pending application Serial No. 273,725. The present application directed to the acid and salt derivatives is a divisional application of Serial No. 273,725, Patent No. 2,300,992.

In the above formulas each compound has at least one unsaturated or alkylene amide group ($-\text{N}$ alkylene group, e. g. allyl) which is capable of reacting with a mercury salt such as mercuric acetate, mercuric sulfate, etc. to yield mercurcation products. When the parent compound has one alkylene or reactive group it is reacted with one mol. of mercury salt to form a mono-mercurated product, and when the parent compound has two or more such groups it is reacted with one, two or the corresponding mols of mercury salt to form mono- or di-mercurated products.

The mercurcation carried out in a suitable aqueous solvent with mercuric acetate results in the formation of mercurated alkyl groups of which the following formulas are illustrative:

By natural hydrolysis, by neutralization with alkali, or by evaporation in vacuo the acetoxy groups are gradually eliminated being replaced by hydroxy groups resulting the formation of mer-

curated alkyl groups of which the following formulas are illustrative:

If another mercury salt, e. g. mercuric propionate, is used for mercurcation the mercurated alkyl groups (except for presence of the corresponding acid radical or $-\text{OCO}$ alkyl group) may be represented by the above formulas. The final products if subject to hydrolysis have the double bond saturated by $-\text{HgOH}$ and $-\text{OH}$ groups.

10 If, as it is frequently desirable to carry out mercurcation in an organic solvent such as methyl alcohol, the final product may have a $-\text{OCH}_3$ group (depending on the alcohol used) in place of the $-\text{OH}$ group attached to the alkyl group represented by the above formula. Other liquids, such as ether, etc., may likewise be employed for the mercuration reaction.

15 If desired, the mercuration products may be isolated as more or less crystalline solids by concentration in *vacuo*, and purified by washing with ether or in the case of those insoluble in dilute acids, by suitable acidification. The soluble products obtained in an aqueous reaction medium may be diluted to the proper concentration 20 and used without isolation. The products containing a free carboxy group (i. e. those containing no solubilizing group such as $-\text{ONa}$, $-\text{NH}_2$) are usually sparingly soluble and are dissolved by the addition of the requisite quantity of alkali.

25 30 35 The following examples describing the preparation of the alkylene amide intermediates and the preparation of the mercuration products therefrom will serve for illustrative purposes:

EXAMPLE I

Mono-mercurated-propylamide, allylamide of phthalic acid

To about 228 grams (4 mols) of allylamine dissolved in dry benzene is added slowly a dry benzene solution containing about 203 grams (1 mol) of phthalyl chloride. At the conclusion of the reaction the reaction mixture is treated with an excess of alkali (e. g. caustic soda solution), the solvent layer separated and distilled. The product remaining after the distillation of the benzene 45 may be distilled in high *vacuo*—or preferably washed with dilute alkali and recrystallized from alcohol. This product, bis-monoallylamide of phthalic acid, melting sharply at 133–135° C., 50 may also be prepared by reacting ethyl phthalate (preferably with gentle heating) with an excess of allylamine. If desired, the original preparation with the acid chloride may be carried out in an aqueous medium by replacing two of the mols of allyl-amine with an equivalent of sodium hydroxide.

55 The mercurcation reaction may be advantageously carried out in water solution as follows: 60 About 25 grams of bis-monoallylamide of phthalic acid prepared, for example, by one of the methods described above, are suspended in about a liter of water and treated slowly, with good stirring, with about 31.5 grams of mercuric acetate. The 65 completion of the reaction may be determined by the absence of the customary tests for the presence of ionic mercury (e. g. no precipitate with NaOH , or no mercuric sulfide precipitate with H_2S , etc.). Any small residue of unreacted amide 70 75 may be separated from the reaction mixture by

filtration. If desired, a mixture of equimolecular amounts of freshly precipitated mercuric oxide and mercuric acetate may be employed for mercuration. The temperature during the reaction may vary from 0°-95° C. without appreciably changing the course of the reaction or the mercuration product produced.

The aqueous solution prepared as above may be used directly after proper dilution for the production of diuresis. In practice it has been found advantageous to partially or completely neutralize the solutions with a base such as sodium hydroxide or ammonium hydroxide. Solutions having pH values of about 6-8 are of increased stability and assist in preventing irritation at the site of injection.

The mercuration reaction may also be carried out in a suitable organic solvent such as methyl alcohol. In this case after the complete removal of the solvent, the solid remaining should be washed with ether. This product dissolved in water gives a solution having the same physiological properties as the mono-mercurated reaction product obtained in the aqueous medium described above.

EXAMPLE II

Mono-mercurated mono-propylamide of phthalic acid

The intermediate product may be prepared by adding about 1 mol. of allylamine to about 1 mol. of finely powdered phthalic anhydride suspended in benzene. The reaction is instantaneous and monoallylamine of phthalic acid separates in excellent yield. This product may be purified by extraction with considerable volume of dry ether or dissolved in sodium hydroxide solution and precipitated by addition of acid. The purified product melts at 110°-112° C.

The mercuration reaction, as indicated in Example I, may be carried out in a number of ways. The following (one of the preferred methods) will serve for illustrative purposes:

To about 20.5 grams of monoallylamine of phthalic acid dissolved in methyl alcohol is added a methyl alcohol solution containing about 31.6 grams of mercuric acetate. After the reaction is complete, the solvent is largely evaporated and the residue then poured into a substantial volume of ether. Analysis of the granular mass which settles out indicates the product to have the following formula:

This product may be solubilized by treatment with one equivalent of alkali hydroxide, e. g. sodium or potassium hydroxide. The alkali salt dissolves readily in water to form stable solutions adaptable for hypodermical administration.

EXAMPLE III

Mono-mercurated monopropyl ureide of phthalic acid

Monoallyl urea and phthalic anhydride in molecular quantities are fused at about 120° C. to form the corresponding allyl ureide melting at 168°-170° C. This product is then mercurated in an aqueous solution with mercuric acetate, sufficient alkali being added from time to time to maintain a clear solution. At the end of sev-

eral days standing a small precipitate forms which may be separated by filtration. The reaction is complete when the clear solution fails to give an immediate dark precipitate with hydrogen sulfide.

In this example the

group is part of a complex substituent. Other compounds represented by the formula

where w equals 0 or 1, 2, 3, etc. are also included within the scope of the present invention. Where w is zero (0) the compound is a ureide prepared from urea as described above. In the following group w equals 2, $-\text{NHCH}_2\text{CH}_2\text{COHN}$ allyl.

It will be obvious to those skilled in the art that the present invention is not limited to the above illustrative examples. The scope of the present invention is accordingly to be determined by the claims annexed hereto.

In the specification and claims it will be obvious that the acyl group of a dibasic acid may be represented by the following formula

where R_1 represents the phenylene radical. It will also be obvious that the alkylene group of the amide is saturated and forms a mercurated alkyl group after mercuration.

I claim:

1. A compound selected from the group consisting of mercurated alkyl amides of dibasic aromatic acids and salts thereof in which the acids are represented by the following formula

in which R_1 is selected from the group consisting of phenylene and homologues thereof, and R_3 represents the mercurated alkyl amide group.

2. A mercurated alkylene amide of an aromatic dibasic acid, the mercury group being attached to the alkylene group of said amide so as to saturate the alkylene group, and the aromatic group of the dibasic acid being selected from the group consisting of phenylene and homologues thereof.

3. A compound having the following formula:

in which R represents an acyl group of a phenylene dibasic acid and in which one of the R' 's is selected from the group consisting of HgOH and HgOCOA' and the other R' is selected from the group consisting of OH and OCOA' , in which the A' 's represent alkyl groups.

4. A compound having the following formula:

in which R represents an acyl group of phthalic acid and in which one of the R' 's is selected from the group consisting of HgOH and HgOCOCH_3 .

and the other R' is selected from the group consisting of OH and OCOCH₃.

5. A compound having the following formula:

in which one of the R's is selected from the group consisting of HgOH and HgOCOCH₃ and the other R' is selected from the group consisting of OH and OCOCH₃.

6. A stable diuretic composition comprising an aqueous solution containing a compound having the following formula:

said solution having a pH value of 6-8.

DONALEE L. TABERN.
